UNITED STATES PATENT OFFICE.

JAMES H. COOK, OF DETROIT, MICHIGAN, ASSIGNOR OF ONE-HALF TO THOMAS J. LYON, OF HOMER, MICHIGAN, AND ONE-HALF TO GRANT C. STEBBINS AND MARKS E. CARR, BOTH OF TULSA, OKLAHOMA.

INJECTOR.

1,159,178.

Specification of Letters Patent.

Patented Nov. 2, 1915.

Application filed January 13, 1915. Serial No. 1,949.

To all whom it may concern:

Be it known that I, JAMES H. COOK, a citizen of the United States, and a resident of Detroit, in the county of Wayne and State of Michigan, have invented certain new and useful Improvements in Injectors, of which the following is a specification.

My invention relates to the supply of fuel to internal combustion engines, and one of the main objects thereof is to provide a device which will distribute fuel equally to all of the explosion chambers in such engines, either two-cycle or four-cycle, under pressure; a further object is to provide means for insuring an initial mixture to the cylinders upon starting the engine; and a further object is to provide such a device which may be used for kerosene oil, gasoline, or other distillates, as fuel.

My invention is fully described in the following specification, of which the accompanying drawings form a part, in which like reference characters are used to designate like parts in each of the views, and in which:—

Figure 1 is a plan view of my injector, partially in section; Fig. 2 is a section taken on the line 2—2 of Fig. 1; Fig. 3 is a section taken on the line 3—3 of Fig. 1; Fig. 4 is a section taken on the line 4—4 of Fig. 1; Fig. 5 is a fragmentary, detached, view of a detail; and Fig. 6 is a fragmentary section, similar to Fig. 4, but showing a modification thereover.

In the drawings forming a part of this application I have shown a valve casing 7 mounted upon a gear case 8 having a shaft 9 arranged longitudinally therein and provided with a cam 10 and a bevel pinion 11 within the gear case and with a sprocket 12 outside of said case, the cam shown in the present instance being one of four points; said shaft is adapted to be rotated, through the sprocket 12, at the speed of the engine shaft for two-cycle engines, and at the speed of the conventional cam-shaft for four-cycle engines, the operative connections with said engine or cam shafts not being shown as they are subject to considerable modification for various makes of engines.

At 13 is shown a seat for a conical valve 14 having a downwardly extended stem adapted to be struck by a rod 15 resting upon the cam 10 whereby said valve may be

intermittently and vertically actuated in the revolution of said cam, a spring 16 insuring the seating of said valve when at rest; said valve is provided with a groove 17 in the side thereof, right hand as shown, of a length approximating 180 degrees of a circle, and with a plurality of notches 18 in the upper edge thereof communicating, when the valve is raised, with an air chamber 19 above the valve and a passage 20 intermediate the height thereof in the casing 7. 55 60 65

The air chamber 19 is in direct communication with a pipe 21 leading to an air compressor or a reservoir for air under pressure, not shown, as either may be employed and of any conventional form; the passage 70 of air to said chamber 19 is controlled by means of a needle-valve 22 having a thread 23 thereon, Fig. 1, engaged with the valve casing in such manner that the rotation of said valve, by means of an arm 24 on the 75 outer end thereof and a push-rod 25, will move said needle-valve 22 away from and toward its seat, the degree of such rotation determining the amount of air under pressure admitted to the chamber 19, and it will 80 be noted that this air in the chamber 19 assists in holding the conical valve 14 on its seat.

Arranged diametrically opposite each other and in the vertical, axial, plane of the 85 valve 14 are two oil ports 26 and 27, Fig. 4, controlled by needle-valves 28 and 29, respectively, each of said needle-valves having a spiral web or thread thereon engaged with the valve casing 7 and the former of 90 which has an arm 30 connected therewith and which arm is in turn connected with the push-rod 25; communicating with the ports 26 and 27, when the respective valves are unseated, are two oil supply pipes 31 95 and 32, respectively, only one of which is in operation as shown because of but one needle-valve, 28, being operatively connected with the push-rod 25, but I may connect either or both of said needle-valves with 100 said rod, as desired, and thus admit oil from the corresponding pipes 31 and 32; this duplicate arrangement of pipes allows me to lead either or both of two different oils to the valve casing 7, according to conditions, 105 but the one operatively connected fuel pipe will suffice for the description of the injector.

Vertically slidable on the shaft 9 is a plate or yoke 33 which is connected, by means of a collar 34, with the end of the rod 15 and, by means of a collar 35, with a rod 36 normally held in lowermost position by means of a coil spring 37, thereby maintaining the rod 15 in lowermost position to permit the valve 14 to find its seat.

By reference to Fig. 5 it will be seen that the degree of rotation of the needle-valves 22 and 28 is not alike because of the different lengths of the arms 24 and 30, the relationship shown insuring a lesser oil supply than of air under pressure, thus insuring a relatively rich mixture, and this relationship also permits of a relatively low pressure for the oil with respect to the air pressure. I may, however, as will be understood, change this relationship to meet varying conditions, either of the kind or character of oil, or climatic, by varying the lengths of the arms 24 and 30, either or both.

The passage 20 communicates with an angular bore 38 in a washer 39 held in place by means of a nut 40 and a screw 41, said bore communicating with a vertical bore 42 in a rotary valve 43 having an outlet port 44 in the side thereof in communication with the vertical bore 42 and in the same horizontal plane as four divergent ducts 45, 46, 47, and 48, leading to the respective tubes 49, 50, 51, and 52, in turn leading to the respective explosion chambers, not shown, and it will be seen that the rotary valve 43 acts as a distributor of the mixture to the engine cylinders.

Said rotary valve 43 is carried by a stem 53 having a bevel pinion 54 on the lower end thereof enmeshed with the pinion 11 on the shaft 9 whereby complemental actuation of the conical valve 14 and the rotary valve 43 results, and it will thus be seen that the mixture in the passage 20 is distributed in equal degree to the different cylinders and in the desired order, and the character of the mixture must be the same in all of the cylinders.

The modification shown in Fig. 6 consists in the provision of a ball check-valve 55 controlled by means of a spring 56 to prevent the air under pressure from forcing the fuel back through the fuel pipe; also, in this form, I provide the valve 14 with an upper post 14^a for guiding a superimposed member 14^b normally separated from the valve 14 by means of a spring 14^c; when the lower valve 14 is raised the fuel may enter around the same before the member 14^b is raised to admit the air under pressure, and thus a very rich, initial, charge of mixture is assured.

It will thus be seen that I provide a substitute for the conventional carbureters which is adapted to oils or distillates, either or both; wherein a small quantity of oil is stored in

the groove 17 of the valve 14 to insure an initial charge which is very rich; wherein the mixture may be enriched or impoverished at will by varying the pressure on the oil; wherein the delivery of the mixture is insured by means of air under pressure; wherein a positive amount of mixture is delivered to the distributor in each actuation of the valve 14 by means of the contact thereof with the cam 10; and wherein complemental actuation of the intake valve 14 and the distributor is positively insured.

While I have shown a present preferred form of embodiment of the device, it will be obvious that I do not limit myself thereto, as many changes in the structure shown may be made to adapt my invention to various types and makes of engines, without departing from the spirit of the invention or sacrificing its advantages.

Having fully described the invention, what I claim as new, and desire to secure by Letters Patent, is:—

1. The combination with an internal combustion engine, of a plurality of intake pipes, a valve casing provided with a mixing chamber, means for delivering air under pressure thereto, means for delivering oil under controlled pressure thereto to vary the character of the mixture, a distributor for delivering positive charges of mixture to said pipes, successively, a valve for controlling the delivery of mixture to said distributor, a shaft, a cam thereon in operative connection with said valve, a pinion connected with said distributor, a pinion enmeshed therewith on said shaft, and means for rotating said shaft.

2. The combination with an internal combustion engine, of a plurality of intake pipes, a valve casing provided with a mixing chamber, a pipe for air under pressure, leading to said chamber, a needle-valve controlling the same, a pipe for oil under pressure, means for controlling said pressure, a needle-valve between said oil pipe and chamber, means for actuating said needle-valves simultaneously in different degrees, a valve between said air pipe and said chamber, a distributor, and means for actuating said last named valve and distributor simultaneously.

3. The combination with an internal combustion engine, of a plurality of intake pipes, a casing in communication therewith provided with a mixing chamber, means for delivering air under pressure thereto intermittently, means for delivering oil under controlled pressure intermittently thereto, and means in the path of said air for containing an initial priming charge of oil adapted to be carried by said air to said pipes previous to the operation of said intermittent oil delivery means.

4. The combination with an internal com-

bustion engine, of a plurality of intake pipes, a casing provided with a mixing chamber, and an air chamber, a valve interposed therebetween, means for delivering air under pressure to said air chamber, means for containing a priming charge of oil in the path of the air from said air chamber to said intake pipes, automatic means for actuating said valve to permit the delivery of 10 said priming charge to said pipes, and means for delivering oil under pressure to

said mixing chamber and air under pressure to said mixing chamber intermittently and simultaneously.

In testimony whereof I have signed my 15 name to this specification in the presence of two subscribing witnesses.

JAMES H. COOK.
